UNITED STATES PATENT OFFICE.

GEORGE B. LIBBY, OF LEHIGH, IOWA.

MACHINE FOR UPSETTING TIRES.

SPECIFICATION forming part of Letters Patent No. 247,667, dated September 27, 1881.

Application filed May 31, 1881. (No model.)

To all whom it may concern:

Be it known that I, GEORGE B. LIBBY, a citizen of the United States, residing at Lehigh, in the county of Webster and State of Iowa, have invented certain new and useful Improvements in Tire-Shrinkers; and I do hereby declare the following to be a full, clear, and exact description of the invention, such as will enable others skilled in the art to which it applies to make and use the same, reference being had to the accompanying drawings, and to letters or figures of reference marked thereon, which form a part of this specification.

Figure 1 is a perspective view of device embodying this invention. Fig. 2 is a bottom-plan view of device shown in Fig. 1.

This invention relates to that class of devices known as "tire-shrinkers;" and the novelty consists in the peculiar construction and combination of the parts making up the machine, all as will now be more fully disclosed and explained.

In the accompanying drawings, A denotes the bed of the machine, mounted on legs α . In this bed A, in suitable openings, α' , are the pieces B, adapted to be moved on the ways b by means of the shaft C, properly hung beneath bed A and operated by arm c. To this shaft are connected the four links D, two on each side. These links severally unite the shaft to the ends of the vertical crank-shafts e of the serrated cam-shaped clamping-jaws E, which shafts e pass down through the movable pieces

B. Thus when the shaft C is rotated motion is communicated to the pieces B to move them back or forth, and also to the shrinkers to revolve them to or from each other. By this construction is secured great power, while at the same time the several parts can be operated in the easiest manner.

This device occupies but small space, and, if desired, other operative parts, such as relate to bending tires and punching and cutting same, may be attached to or mounted on the same bed or table.

This device is easily operated, and since the power developed is very great and the construction of the same quite simple, it is evident that a very excellent machine or device is produced by my invention.

Having thus described my invention, what I consider new, and desire to secure by Letters Patent, is—

The tire-upsetter herein described, consisting of sliding pieces B, mounted on ways b in openings α' of table or bed A, on which pieces B are pivoted the revoluble clamping-jaws E, having serrated faces, in combination with shaft C, links D, and vertical crank-shaft e, substantially as and for the purposes described.

In testimony whereof I affix my signature in presence of two witnesses.

GEORGE B. LIBBY.
